UNITED STATES PATENT OFFICE.

JOHN C. PARKER, OF PHILADELPHIA, PENNSYLVANIA.

STEAM BOILER.

Application filed July 29, 1922. Serial No. 578,306.

This invention relates to steam boilers of the water tube type, and it is designed primarily to provide a down-flow boiler with a new arrangement of tubes and connections, 5 for the purpose of improving the circulation by providing means for entraining the water and steam, facilitating evaporation, simplifying the construction and avoiding prior structural defects.

10 This invention is characterized, in its preferred form, by the combination, with a steam and water drum, of a down-take connected by a horizontal inlet box at the rear of the boiler with serially arranged tubes 15 comprising two tubes extending forward and upward from said inlet box to respective horizontal return junction boxes in the front of the boiler, two tubes extending from the respective junction boxes last named rearward and downward to the tops of respective vertical junction boxes in the rear of the boiler, two tubes extending from the bottoms of the respective boxes last named forward and upward to horizontal junction boxes in 20 the front of the boiler, and so on, for any number of tubes high, to two tubes extending rearward and downward from respective horizontal boxes in the front of the boiler to the tops of respective vertical junction 25 boxes of extended height in the rear of the boiler, two tubes extending forward and upward from the bottoms of the boxes last named to respective horizontal junction boxes in the front of the boiler, and two 30 tubes extending rearward and upward from the boxes last named, between elongated vertical boxes and beneath other vertical junction boxes aforesaid to upcasts connected with the steam and water drum.

35 It will be understood that this specific arrangement, comprising two double elements of a boiler, is set out by way of illustrating a preferred type of construction and not by way of limitation of the invention.

40 A boiler having the novel circulating system specified affords an extended heating surface, produces rapid circulation, effects a highly desirable entrainment of steam and water, facilitates evaporation, prevents trapping 45 the steam and water, avoids overheating the tubes, secures economy in the production of steam and avoids structural defects.

Desired circulating conditions have been obtained by the elongation of the lowermost 50 vertical junction boxes of each circulating element so as to give the two reversely ex-

tending bottom tubes the necessary rise or upward inclination in the direction of flow to secure the rapid movement of all the steam or steam and water therein.

55 The specified arrangement has the added advantage that it gives more area for the passage of gases in the lower part of their course, while they are expanded at a high temperature, due to staggering the tubes 60 so as to make two rows in place of one with the same number of tubes at the rear end where the gases pass upward at the end of the first baffle.

65 A further desideratum attained by the arrangement of the tubes is the facility provided for baffling the gases of highest temperature and greatest expansion, to effect the most efficient heat exchange and steam generation.

70 In the accompanying drawings, Fig. 1 is a vertical sectional view taken longitudinally through a boiler embodying a preferred form of my invention; Fig. 2 is a front part sectional elevation of the construction illustrated in Fig. 1; Fig. 3 is a rear part sectional elevation of the construction illustrated in Fig. 1, and Fig. 4 is a broken perspective view of two sets of tubes 75 detached from the construction illustrated in Fig. 1.

75 The construction shown in the drawings, by way of illustrating a preferred form of my invention, comprises the walls A together with the roof B, within which are set the 80 steam and water drum C and the sets of continuous tubes D¹ to D¹⁴ which are connected with the rear end of the drum by the downtakes D and the upcasts D¹⁵.

85 Each downtake D delivers from the drum C to a horizontal inlet box E in the rear of the boiler, from which box two parallel tubes D¹ extend forward and upward to respective horizontal junction boxes E¹ in the front of the boiler. From these junction boxes E¹ respective parallel tubes D² extend rearward and downward to the tops of the respective vertical junction boxes E² in the rear of the boiler. From the bottoms of these boxes E² parallel tubes D³ extend forward and upward to horizontal junction boxes E³ in the front of the boiler. From these boxes E³ parallel tubes D⁴ extend rearward and downward to the tops of the respective vertical junction boxes E⁴ in the rear of the boiler below the inlet boxes E. From the bottoms of the respective boxes E⁴ parallel

tubes D^5 extend forward and upward to respective horizontal junction boxes E^5 . From the respective boxes E^5 parallel tubes D^6 extend rearward and downward to the tops of the respective junction boxes E^6 in the rear of the boiler. From the bottoms of respective boxes E^6 parallel tubes D^7 extend forward and upward to respective horizontal junction boxes E^7 in the front of the boiler. From the respective boxes E^7 parallel tubes D^8 extend rearward and downward to the tops of vertical junction boxes E^8 in the rear of the boiler. From the bottoms of the respective boxes E^8 parallel tubes D^9 extend forward and upward to horizontal junction boxes E^9 in the front of the boiler. From the respective boxes E^9 parallel tubes D^{10} extend rearward and downward to the tops of vertical junction boxes E^{10} in the rear of the boiler. From the bottom of respective boxes E^{10} parallel tubes D^{11} extend forward and upward to horizontal junction boxes E^{11} in the front of the boiler. From the respective boxes E^{11} parallel tubes D^{12} extend rearward and downward to the tops of junction boxes E^{12} of approximately double the depth of the previously specified vertical boxes occupying higher positions. From the bottom of the respective boxes E^{12} parallel tubes D^{13} extend upwardly to respective horizontal junction boxes E^{13} in the front of the boiler. From the respective boxes E^{13} parallel tubes D^{14} extend rearward and upward to angle boxes E^{14} connecting them with the upcasts D^{15} , the tubes D^{14} thus extending through open spaces beneath boxes E^{10} and above the bottoms of the elongated boxes E^{12} .

The tubes D^2 have the baffle F disposed thereon so as extend from their rear ends forward say two-thirds of their length and the tubes D^{14} have the baffle F^1 disposed thereon so as to extend from their forward ends rearward say two-thirds of their lengths. The upflow tubes D^{13} and D^{14} are in the primary combustion chamber G , subject to the hottest condition of the gases, which flow from the primary combustion chamber through the passage between baffles F^1 and F in contact with the tubes therein and thence into contact with the drum C .

It will now be seen that this arrangement provides an extended course for circulating water back and forth through the heating zones with correspondingly extended heating surfaces. The general downward flow of the water is modified so that it is required to entrain the steam. The steam or steam and water are caused to flow upward through the bottom tubes and the tubes connecting them with the upcasts, with resulting avoidance of trapping, inducement of rapid circulation, prevention of overheated tubes, and provision for better heating.

Having described my invention, I claim:

1. In a downflow steam boiler, a water circulating and steam generating element having a set of serially arranged tubes disposed in vertical rows and comprising oppositely inclined bottom tubes, each forming the lowermost tube of a vertical row. 70

2. In a downflow steam boiler, the combination with a steam and water drum, of a water circulating and steam generating element having a set of serially arranged tubes forming a plurality of vertical rows and comprising oppositely inclined bottom tubes each forming the lowermost tube of a vertical row, a down-flow tube connecting said drum with an upper tube of said element, and an up-flow tube connecting said drum with the higher end of one of said bottom tubes. 75

3. In a steam boiler, a water circulating and steam generating element having a set of serially arranged tubes disposed in vertical rows and comprising upper tubes which are similarly disposed and through which flow is alternately upward and downward and bottom tubes which are reversely disposed and through both of which flow is upward. 80

4. In a steam boiler, the combination with a steam and water drum, of a water circulating and steam generating element having a set of serially arranged tubes disposed in vertical rows and comprising similarly disposed upper tubes through which the flow is alternately upward and downward and oppositely inclined bottom tubes in which the flow is upward, a downflow passage connecting said drum with an upper tube of said element and an upflow passage connecting said drum with the higher end of the last lower tube. 95

5. In a steam boiler, the combination with a steam and water drum, of a downtake, a junction box connected with said downtake, a plurality of steam generating and water circulating elements connected with said junction box, and upcasts through which the respective elements discharge to said drum, each of said elements comprising a set of tubes connected in series by vertical junction boxes at one end thereof and horizontal junction boxes at the other end thereof, the two lowermost tubes of the series being connected and inclined in opposite directions, so as to secure upward flow therethrough to said upcast. 110

6. In a steam boiler, the combination with a steam and water drum, of a plurality of water circulating and steam generating elements each having a set of tubes and junction boxes arranged in series with the upper tubes similarly inclined and the bottom tubes oppositely inclined and conduits connecting said elements in circuit with said drum, each of said elements having tubes thereof con- 115

nected at one end by horizontal junction boxes and at the other end by vertical junction boxes, the lowermost of which is relatively elongated, whereby the last tube of

5 the series passes above the connection with said elongated box of the oppositely inclined bottom tube.

7. A downflow boiler comprising a gener-

ating element having serially arranged tubes disposed in a plurality of vertical rows, the 10 bottom tubes of the respective rows being inclined oppositely to one another.

In testimony whereof I have hereunto set my name this 28th day of July, 1922.

JOHN C. PARKER.
